TUBE AND METHOD OF MAKING THE SAME

Albert M. Goldstein, Far Rockaway, and Harry Schoen, Brooklyn, N. Y., assignors to Eagle Straw Corporation, Brooklyn, N. Y., a corporation of New York

Application September 10, 1936; Serial No. 100,096

20 Claims. (Cl. 41—21)

The present invention relates to the manufacture of tubes. In its more specific aspects, the invention is concerned primarily with tubes commonly known as drinking straws, although the invention may be practiced in connection with the manufacture of other tubes.

This invention may be utilized with special advantage in the production of drinking straws or other tubes composed of or containing transparent cellulose material such as, regenerated cellulose, and cellulose acetate, and one of the objects of the invention is to produce such tubes in one or more colors in addition to the normal or water white color of transparent cellulose material.

Another object of the present invention is to provide an economical and efficient method of producing colored tubes composed in whole or in part of transparent cellulose material.

Another object of the present invention is to produce tubes of any particular color, including the normal color of the material, with surface ornamentation whereby to improve the appearance of such tubes so as to encourage a more extensive use thereof, especially in the home, as at parties, entertainments, etc.

A yet further object of the invention is generally to provide an economical and efficient method of ornamenting drinking straws and other tubes.

The above objects of the invention and other objects ancillary thereto will best be understood from the following description considered with reference to the accompanying drawings.

more or less diagrammatically, a modification of the invention;

Fig. 12 is a top plan view of part of the apparatus illustrated in Fig. 1, on a larger scale, and illustrating a modification.

In practicing the present invention, the tubes are formed by spirally winding superposed strips of material on a mandrel, in accordance with more or less conventional tube-manufacturing methods. In performing this method, cellulose acetate material, such as "Protectoid" or "Kodapak," or other non-fibrous cellulosic sheet material, is provided in the form of rolled strips of a suitable width, say $\frac{1}{8}$ of an inch when the material is used for making drinking straws. As

shown in Fig. 1, the strips 10 and 12 of such material are supplied from rolls 14 and 16 to a mandrel 18 on which said strips are spirally wound in the usual manner by means of a spinning belt 20. The strips 10 and 12 are caused to unite on the mandrel by reason of the treatment of the strip 10 with a solvent for the material of said strip, whereby the latter is softened and caused to merge with the strip 12 when spirally wound therewith on the mandrel 18, the pressure of the belt 20 promoting the union between said strips. The continuous tube, as it comes off the mandrel, is cut into suitable lengths by cutting mechanism (not shown). The cutting mechanism disclosed in the application of Schoen and Pletcher, Serial No. 692,604, filed Oct. 7, 1933, is preferred.

The solvent is applied to the strip 10 as the latter passes from the roll 14 to the mandrel. This may be accomplished in any suitable way.

For example, as here shown more or less diagrammatically, the solvent may be applied by means of a roller 22 which engages another roller 24 which dips into the solvent contained in the pan 26. In accordance with the present invention, the strip 10, prior to the treatment with the solvent, is colored by moistening the same with a liquid coloring agent, preferably aniline, or other suitable coloring material which may be dissolved in a solvent which is also a solvent for the material of the strip. For example, when the strip 10 is composed of cellulose acetate the solvent for the coloring material, and for the material of the strip, may be ethylene glycol monomethyl ether, which is sold under the trade name "Methyl Cellosolve." Said coloring material in the solvent may be applied to the strip 10 by a roller 28 which is engaged by a roller 30 which dips into the liquid coloring agent contained in the pan 32. A guide pulley 34 and a

Fig. 2 is a perspective view of part of the apparatus illustrated in Fig. 1, on a larger scale;

Figs. 3 and 4 are side and front views, respectively, on a larger scale, of a part of the apparatus illustrated in Fig. 1;

Fig. 5 is a sectional view on the line 5—5 of Fig. 3;

Fig. 6 is a sectional view on the line 6—6 of Fig. 4;

Figs. 7 and 8 are fragmentary side views of tubes produced in accordance with the present invention;

Figs. 9 and 10 are plan views of strip fragments illustrative of the present method;

Fig. 11 is a side view in elevation, illustrating

tensioning device 36 are associated with the strip coloring device for guiding said strip and regulating the tension thereof. A guide pulley 38 and a pressure roll 40 are associated with the solvent applying device. As the liquid coloring agent for the strip 10 is also a solvent for said strip material, the solvent applying device hereinbefore referred to may be omitted, but as improved results are obtained by first applying the coloring material in the solvent and subsequently again moistening the strip with solvent, the use again moistening the strip with solvent, the use of said solvent applying device in addition to the coloring device is preferred.

After the strip 10 is thus treated with the solvent, said strip instead of passing directly to the mandrel from the roll 22 is caused to travel a suitable distance until the solvent has evaporated to a considerable extent, thereby partially drying the strip and thus avoiding moistening of the mandrel with the solvent. For this purpose, the strip 10 is conducted to a drying device 42, including spaced rollers 44 and 46, over which said strip is caused to pass and thereby subjected to the drying action of the atmosphere prior to being wound with the other strip on the mandrel. As best shown in Figs. 3 and 4, the drier 42 comprises a bar 48 supported on the frame 50 of the apparatus by the pin 52 secured in said frame. Said bar has a split end portion 54 which is clamped to a reduced portion 56 of the pin 52 by a stud bolt 58. A spindle 60, on which the roller 44 is freely rotatable, is adjustably fixed in the bar 48 by means of a set screw 62. A rod 64 is carried by and projects from the upper end of the bar 48. A bracket 66, having a split end 68, is clamped to said rod in adjusted position by a stud bolt 70. The spindle 72, on which the roller 46 is freely rotatable, is supported by said bracket 66, being clamped therein by the action of the stud bolt 74 in engagement with the split bracket end 76. Cotter pins 78 and 80 passing through the spindles 60 and 72, respectively, hold the rollers 44 and 46 on said spindles. A guide 82, as best shown in Figs. 3 and 5, is secured to the bar 48 by a screw 84. Said guide comprises spaced confronting end portions 86 and 88 defining an open-ended slot 90 within which the strip 10 moves as it passes between the rollers 44 and 46. Said guide 82 is provided with a slotted portion 92 which is engaged by the bolt 84 for adjustable securing of the guide to the bar 48. It will be observed that by adjusting the roller 46 longitudinally of the rod 64, the time of exposure of the strip 10 to the atmosphere for drying purposes may be varied. It will be noticed that the strip 10, after it leaves the solvent applying roller 22, passes under the guide pin 51 in engagement with the roller 44 and then upwardly and over the roller 46, then downwardly and under the roller 44, and then to the guide member 41, from which the strip passes to the mandrel 18. The strip 12 passes from the roll 16 beneath the pin 51 through the guide and retarding member 43, and then to the mandrel upon which it is spirally wound together with the strip 10 to form the colored tube, illustrated in Fig. 7.

The preferred method of coloring predetermined parts of the strip 10 whereby to produce the desired design or ornamentation of the tube will now be described. Referring first to Fig. 1, it will be observed that the strip 10 passes over, and in contact with a member 100 which applies a coloring agent to the surface of said strip 10, forming a stripe 102 on said strip extending

longitudinally between the side edges thereof, as shown more clearly in Figs. 2 and 9. When the strip 10 with the applied stripe is wound on the mandrel together with the strip 12 a tube 104 (Fig. 8) having a helical stripe 106 is produced. Various other designs may be produced, as for example, by applying a plurality of stripes 102 to the strip 10 in the same or contrasting colors, and in various other ways which will occur to those skilled in the art in view of the present disclosure.

As illustrated in Fig. 2, the striping member 100 comprises a wick carried by a screw-threaded holder 108 removably and adjustably mounted in a support 110, secured to the frame 50. Provision is made for mounting a plurality of wick holders 108 in the support 110, said support having a plurality of screw-threaded openings 112 through which the holders 108 project. Said openings 112 are spaced laterally from each other so that the striping members 100 may engage the surface of the strip at laterally spaced points thereby producing spaced stripes on the strip. The wick is immersed in the coloring liquid which is preferably a mutual solvent for the coloring material and for the material of the strip, as in the case of the coloring material described above for coloring the strip. As illustrated in Fig. 2, provision is made for applying a plurality of stripes of different colors to the strip and for this purpose a plurality of containers 114 are disposed below the support 110 on a shelf 116 secured to the frame 50. The coloring material for striping or ornamenting is preferably applied so that it will be at the welded seam portions of the tube.

When the stripes are applied to the material of the tube, specifically to the strip 10, as just described, and the strip is wound on the mandrel together with the strip 12 to form the tube, the stripes are disposed on the inner surface of the outer strip of the tube but are visible as the material of the tube is transparent. Said stripes may, however, be applied to the outer surface of the strip 10, and should be applied to said surface when the strip is composed of opaque "Protectoid," "Cellophane" or other similar material, or when the stripes are applied to opaque paper strips of the character utilized in making paper drinking straws. In the latter case, the stripes will be visible through the wax waterproofing coating applied to the tubes after they are formed on the mandrel. Also, instead of utilizing a striping device there may be utilized a dotting or stippling device, or as illustrated in Fig. 11, the design may be applied to the strip 10 by a printing device 120 (Fig. 11). As here shown, the printing device is substituted for the striping device shown in Fig. 1, and like the latter is preferably positioned between the coloring device including the roll 28 and the solvent applying device including the roll 22. Said printing device 120 may be of any well known form, and as herein diagrammatically shown, may comprise an engraved roller 122 which is supplied with coloring or suitable printing material by a roller 124 which dips into the coloring material in the pan 126. A platen or pressure roll 128 is arranged to engage the strip 10 and hold the same against the printing roller 122. While the printing of the strip for the application of the design to the latter, as the strip is supplied from the roll 14 to the mandrel, is preferred, it will be understood that the roll 14 may comprise pre-printed or ornamented material in one or more colors, in which case the printing or strip-

ing of the strip as it is supplied to the mandrel will be unnecessary.

It is also within the scope of the present invention to ornament the tube after it is formed, and this may be done in lieu of, or in addition to the ornamentation applied to the strip prior to the winding thereof on the mandrel. Thus, as illustrated in Fig. 12, for example, a tube-ornamenting device 130 is disposed adjacent the mandrel 18 and is arranged to apply the coloring material to the material of the tube after the latter is formed. Said device, as here shown by way of illustration, comprises a striping member 132 which is preferably a wick carried by a holder 134, adjustable in a plate 136, and positioned over a pan 138 of coloring material in which the end of the wick is immersed. Said striping member 132 is preferably positioned between the belt 20 and the free end of the mandrel. As the striping member 132 is stationary and as the tube revolves on the mandrel, said striping member is effective to produce on the tube a helical stripe similar to that illustrated in Fig. 8. Obviously, a plurality of striping members 132 may be arranged to produce a plurality of stripes on the tube.

After the surface design is applied to the material of the tube, either before the material is wound on the mandrel, or after it is wound on the mandrel and the tube formed, the manufacturing operations of the tube are completed. In the case of tubes made from strips of paper, they are cut into suitable lengths as they come off the mandrel, and subsequently the cut tubes are coated with wax to render them waterproof. In the case of tubes made of the cellulose material, as described above, the tube is cut into suitable lengths as it leaves the mandrel, but no waterproofing thereof is necessary as the material of the tube is non-absorbent, moisture proof and non-hygroscopic.

While we have illustrated the devices for applying various designs to the strip or to the tube formed by winding the strip on the mandrel, it will be understood that the devices herein disclosed are merely illustrative of the various ways of practicing the present method. It will be further understood that the method of applying the designs to the strip or to the tube may be performed by hand, in which case the devices hereinbefore referred to may be dispensed with. Thus, for example, we have produced ornamented tubes by manually applying the coloring material to the strip 10, and more particularly to the surfaces thereof, which is positioned internally of the tube after the latter is formed, by holding a sponge or wick, moistened with the coloring material, in engagement with said surface as the strip passes from the roll 14 to the mandrel. In that case, the design was applied at a point between the color applying device and the solvent applying device. It will be further understood that the design may be applied to the strip 10, whether or not the strip is colored as described above, by the apparatus herein illustrated or whether said strip has no color other than the normal color of the material. It is also within the scope of the present invention to form the tube in part at least of opaque sheet material. Thus, for example, the inner strip or layer 12 may be opaque and the outer strip or layer may be transparent and the coloring material applied to the outer surface of the inner strip or to the inner surface of the outer strip or otherwise applied so that in the finished tube it is

disposed between the inner and outer tube surfaces and visible externally of the tube by reason of the transparency of the outer layer or strip. It will be understood further that in the production of colored tubes, in accordance with the present invention, there may be utilized strips of pre-colored material, and for accomplishing the object of the present invention, that is to produce colored tubes, only one of the strips, preferably the outer strip, need be colored. When the outer strip 10 is transparent the inner strip may be colored or ornamented, in which case it will be unnecessary to color or ornament the outer strip 10, or a pre-colored or pre-ornamented inner strip 12 may be utilized instead of the pre-colored or pre-ornamented strip 10. The inner strip 12 when ornamented or colored as it is supplied to the mandrel may be treated in the same way as that described above in connection with the strip 10, and the coloring material with or without additional striping or ornamenting will be applied to the surface thereof which will be disposed next to the surface of the outer strip 10 in the tube. Various other changes and modifications of the invention herein disclosed will suggest themselves to those skilled in the art, in accordance with the teachings herein contained. Therefore, we do not wish to be limited precisely to the method or constructions, or designs applied to the tubes, or to any other part of the present disclosure, except as may be required by the appended claims considered with reference to the prior art, and unless otherwise specifically stated, the steps in the method may be performed in a sequence which differs from the order of their recitation in the claims.

Having described our invention, what we claim and desire to secure by Letters Patent is:

1. In the method of making a tube from strips of suitable material according to which method the strips are unwound from strip rolls and simultaneously are spirally wound on a mandrel to form the tube, the step of treating one of said strips to cause the same to unite with another strip when spirally wound together on the mandrel, applying a coloring agent to a part only of the width of the surface of one side of one of said strips longitudinally thereof while it is being unwound from its roll and prior to the winding thereof on the mandrel, and winding said strips on the mandrel thereby forming a tube having a surface in contrasting colors.

2. In the method of making a tube from strips of suitable material according to which method the strips are unwound from strip rolls and simultaneously are spirally wound on a mandrel to form the tube, the steps of coloring one of said strips and simultaneously treating the same to cause it to unite with another strip when spirally wound together on the mandrel, simultaneously applying a coloring agent to a part only of the width of the surface of one side of said treated strip longitudinally thereof while it is being unwound from its roll and prior to the winding thereof on the mandrel, and winding said strips on the mandrel thereby forming a tube having a surface in contrasting colors.

3. The method of making colored transparent drinking "straws" from strips of transparent sheet material capable of being softened by a solvent for said material, according to which method the strips are unwound from strip rolls and simultaneously are spirally wound on the mandrel to form the tube, said method comprising color-

ing one of said strips as it is unwound from its roll, the coloring agent being contained in a solvent therefor and for said strips, and winding said colored strip together with another strip in overlapping relation on said mandrel whereby said strips are united to form a multi-layer tube.

4. The method of making tubes from a plurality of strips of suitable material which comprises spirally winding said strips together and uniting the same in superposed relation to form a tube, applying a surface design to the material of the tube during the winding of said strips on the mandrel, and after the said strips are wound together and united to form the tube, cutting the latter into suitable lengths.

5. The method of making tubes from a plurality of strips of suitable material which comprises applying coloring material to a surface of at least one of said strips, spirally winding said strips together and uniting the same in superposed relation to form a tube while the coloring material is being applied to said surface of one of the strips, and after the said strips are wound together and united to form the tube cutting the latter into suitable lengths.

6. The method of making colored transparent tubes, which comprises associating a plurality of strips of transparent sheet material, applying a stripe of coloring material of less width than the width of the strip and contained in a solvent for said strips to at least one of said strips, and spirally winding said strips together and uniting the same to form a tube while the coloring material is being applied to said one of the strips.

7. A tube comprising a plurality of strips of transparent and waterproof non-fibrous cellulosic sheet material spirally wound together in superposed relation, at least one of said strips having coloring material thereon between its side edges and extending spirally of the tube for ornamenting said tube, said strips being secured together in said relation by a substance which contains said coloring material.

8. A tube comprising a plurality of strips of transparent and waterproof non-fibrous cellulosic sheet material including an inner strip and an outer strip spirally wound and fused together in tube formation, and a stripe of coloring matter on the material of the tube between the inner and outer surfaces thereof and of less width than the width of the strip, said coloring matter being contained in a solvent for the material of said strips for fusing them together in tube formation, said coloring matter being visible through the material of the tube externally of the latter by reason of the transparency of said cellulosic sheet material.

9. A tube comprising a plurality of layers of material extending in continuous relation peripherally and longitudinally of the tube, including an inner layer and a transparent outer layer of non-fibrous cellulosic sheet material, and a stripe of coloring material of less width than the width of the cellulosic sheet between said inner and outer layers, said strips being secured together in said relation by a substance which contains said coloring material, said coloring material being visible externally of the tube, by reason of the transparency of said outer layer.

10. A tube comprising a plurality of strips of sheet material including an inner strip and an outer strip spirally wound together in tube formation, said outer strip being composed of transparent non-fibrous cellulosic sheet material, and a stripe of coloring material of less width than

the width of the strip between the adjacent surfaces of said strips, said coloring matter being contained in a solvent for the material of said strips for fusing them together in tube formation, 5 said coloring material being visible externally of the tube by reason of the transparency of said outer layer.

11. In the method of making a tube from strips of suitable material according to which method 10 the strips are spirally wound on a mandrel to form the tube, passing a plurality of said strips to the mandrel, applying a coloring agent to one of said strips in the course of its travel to the mandrel, treating one of said strips to cause it 15 to unite with another strip when spirally wound together on the mandrel, and winding said strips on the mandrel to form the tube.

12. In the method of making a tube from strips of suitable material according to which method 20 the strips are spirally wound on a mandrel to form the tube, passing a plurality of said strips to the mandrel, applying a coloring agent to a part only of the width of one of said strips in the course of its travel to the mandrel, treating 25 one of said strips to cause it to unite with another strip when spirally wound together on the mandrel, and winding said strips on the mandrel thereby forming a tube having a surface in contrasting colors.

13. The method of making a tube from strips of suitable waterproof sheet material capable of being softened by a solvent for said material, according to which method the strips are spirally wound on a mandrel to form the tube, said method comprising passing a plurality of said strips to the mandrel, moistening one of said strips with a solvent therefor in the course of its travel to the mandrel, applying a coloring agent to one of said strips in the course of its travel to the mandrel, said coloring agent being contained in said solvent, and while the solvent treated strip is still soft winding the same together with another of said strips on said mandrel to form the tube.

45 14. The method of making colored drinking "straws" from strips of suitable sheet material capable of being softened by a solvent for said material, according to which method the strips are spirally wound on a mandrel to form a tube, said method comprising passing a plurality of said strips to the mandrel, moistening at least one of said strips, in the course of its travel to the mandrel, with a solvent therefor carrying a coloring agent whereby said strip is simultaneously colored and rendered adhesive, and then while 50 said colored strip is still soft winding the same together with another strip of said material on said mandrel to form the tubes.

15. The method of making colored transparent drinking "straws" from strips of transparent sheet material capable of being softened by a solvent for said material, according to which method the strips are spirally wound on a mandrel to form the tube, said method comprising 60 passing a plurality of said strips to the mandrel, moistening at least one of said strips, in the course of its travel to the mandrel, with a solvent therefor carrying a coloring agent whereby said strip is simultaneously colored and rendered adhesive, applying to a part only of one surface of one of said strips a coloring agent which contrasts with the color of said strip, and while the solvent treated strip is still soft winding the same together with another of said strips on said mandrel to form a tube in contrasting colors.

16. In the method of making a tube from strips of suitable material according to which method the strips are spirally wound on a mandrel in overlapping relation forming inner and outer layers of the tube, passing a plurality of said strips to the mandrel, applying a coloring agent to one of said strips, in the course of its travel to the mandrel and to a surface portion thereof which is overlapped by another of said strips when wound on the mandrel, and then treating one of said strips to cause it to unite with another of said strips, and winding said strips on the mandrel to form the tube.

17. In the method of making a tube from strips of suitable material according to which method the strips are spirally wound on a mandrel in overlapping relation forming inner and outer layers of the tube, passing a plurality of said strips to the mandrel, applying a coloring agent to the inner surface of the strip which forms the outer tube layer, while said strip is passing to the mandrel, and then treating one of said strips to cause it to unite with another of said strips, and winding said strips on the mandrel to form the tube.

18. The method of making a tube from strips of suitable waterproof sheet material capable of being softened by a solvent for said material, according to which method the strips are spirally wound on a mandrel in overlapping relation forming inner and outer layers of the tube, said method comprising passing a plurality of said strips to the mandrel, moistening one of said strips, in the course of its travel to the mandrel, with a solvent for the strip material, applying a coloring agent to the inner surface of the strip which

forms the outer tube layer, while said strip is passing to the mandrel, and while the solvent treated strip is still soft winding the same together with another of said strips on said mandrel to form a tube in contrasting colors.

19. The method of making colored transparent drinking "straws" from strips of transparent sheet material capable of being softened by a solvent for said material, according to which method the strips are spirally wound on a mandrel in overlapping relation forming inner and outer layers of the tube, said method comprising passing a plurality of said strips to the mandrel, moistening one of said strips, in the course of its travel to the mandrel, with a solvent for the strip material, applying a coloring agent to the inner surface of the strip which forms the outer tube layer, while said strip is passing to the mandrel, and while the solvent treated strip is still soft winding the same together with another of said strips on said mandrel to form a tube in contrasting colors.

20. A drinking "straw" or tube comprising a plurality of strips of waterproof non-fibrous cellulosic sheet material spirally wound together in superposed tube-forming relation, at least one of said strips having coloring material on a surface thereof disposed between the inner and outer surfaces of the tube for ornamenting the latter, the outer strip being sufficiently transparent to disclose said coloring material, said strips being secured together in said relation by a substance which contains said coloring material.

ALBERT M. GOLDSTEIN.

HARRY SCHOEN.
